United States Patent Office

Des. 206,104
Patented Oct. 25, 1966

206,104

AIRCRAFT WEAPON SUPPORT

John P. Fosness, Columbus, Ohio, assignor to
North American Aviation, Inc.

Filed Sept. 15, 1965, Ser. No. 87,005

Term of patent 14 years

(Cl. D71—1)

FIG. 1 is a perspective view of an aircraft weapon support having my new design;

FIG. 2 is a plan view thereof;

FIG. 3 is a side elevational view thereof; and

FIG. 4 is an end elevational view thereof at increased scale.

I claim:

The ornamental design for an aircraft weapon support, as shown.
